UNITED STATES PATENT OFFICE.

SAMUEL FRIEDMAN, OF BROOKLYN, NEW YORK.

STRETCHER FOR CASE SKINS.

Application filed April 18, 1923. Serial No. 632,979.

To all whom it may concern:

Be it known that I, SAMUEL FRIEDMAN, a citizen of the United States of America, and a resident of the city of New York, 5 borough of Brooklyn, in the county of Kings and State of New York, have invented a new and Improved Stretcher for Case Skins, of which the following is a description.

My invention relates to stretching what 10 are known as case skins, that is to say, skins into which the stretcher elements may be inserted and then separated to stretch and enlarge the case skin. The means generally employed for stretching case skins are 15 mounted on the top of the table and the supporting base and other parts appurtenant to the stretcher offer more or less of an obstruction on the table and limit the clearance space above the table so that the operator is 20 required to have a considerable reach over the table for the placing and removal of the skin and for actuating the movable stretching element.

The general object of my invention is to 25 overcome the objectionable conditions referred to and this object I accomplish by providing a construction in which the supporting base of the stretcher is secured beneath the table and the stretcher elements 30 have a form to extend outwardly, upwardly and then laterally inward to overlie the table.

A further object of my invention is to provide an operating means for the movable 35 stretcher element disposed for the main part beneath the table and having an arm projecting laterally outward to be disposed in position for the operator to lean against the same and thereby promoting convenience in 40 the application of the pressure to the operating means.

A more specific object of the invention is to provide for folding the pressure arm of the operating means to an inner position 45 when not in use so as not to offer an obstruction materially beyond the table edge.

Reference is to be had to the accompanying drawings forming a part of this specification, it being understood that the drawings are merely illustrative of one example 50 of the invention.

Figure 1 is a plan view showing a portion of the table equipped with my improved stretcher and operating means therefor;

Figure 2 is an enlarged inverted plan

view of the stretcher and operating means as applied to the table;

Figure 3 is a front view of said stretcher as applied to the table;

Figure 4 is a transverse vertical section as 60 indicated by the line 4—4, Figure 3.

In carrying out my invention in accordance with the illustrated example, I provide a base plate 10 adapted to be secured to a table top A at the under side as by screws 65 11 or equivalent means. The base supports a fixed stretcher element 12 and a co-acting movable stretcher element 13. Said stretcher elements are in general of U-shape form, one leg lying beneath the table top 70 along the base 10 and the other leg of the U extending laterally inward and overhanging the table top a proper distance above the latter, whereby to provide stretcher arms 14, 75 15 on the respective elements 12, 13. The fixed element 12 is securely bolted or otherwise suitably fastened to the base plate. The movable stretcher element 13 is adapted to slide on two parallel guide rods 17 supported on the base 10. 80

For operating the stretcher element 13 use is made of a lever 18 disposed beneath the table top and fulcrumed at its inner end as at 19 to a corner of the base 10. A link 20 is riveted or otherwise fastened at one end as at 21 to the stretcher element 13 and at the opposite end said link is secured by a bolt 22 to the lever 18, the link being provided with a longitudinal series of bolt holes 23 for adjusting the throw of said element 12. One end of the lever 18 is in the form of a pressure arm 24 pivotally mounted at the inner end as by a rivet 25. The arm 24 when the machine is to be operated 90 is swung to a position projecting laterally 95 outward beyond the table top A but the pivot 25 permits of the arm being folded inwardly adjacent the edge of the table so as to offer no obstruction. The pivotal movement of the arm 24 to the outer position is 100 limited by providing on the main section of the lever and on the said arm 24 shoulders 29 and 30 respectively. A retractile coil spring 26 is secured at one end to a lug 27 or other fixed part of the frame 10 and the 105 other end of said spring is secured to a lug 28 or other fixed part of lever 18.

With the described construction when the arm 24 is swung to the outer position as indicated in Figures 1 and 2, the operator of 110

the stretcher may lean his body against said arm and by exerting lateral pressure on the arm swing the lever 18 on its fulcrum 19 and thereby through the link 20 moving the 5 stretcher element 13 away from the element 12 thus separating the stretcher arms 14, 15 and extending or stretching the skin that has been slipped onto said stretcher arms or juxtaposed as in Figure 1. Upon the operator 10 removing the pressure against the arm 24 the spring 26 restores the lever 18 and the stretcher elements 12, 13 to the original positions. It will be seen that when the described stretcher is emplaced on the table 15 only the stretcher arms 14, 15 will be disposed over the table, the remainder of the surface of the table affording clearance for the skin and for the movements of the operator's hands and arms in the operation of 20 stretching. The construction results also in the stretcher arms 14, 15 being disposed close to an edge of the table instead of being emplaced laterally inward from the table edge as is usual. The nearness of the 25 stretcher arms to the edge of the table greatly promotes convenience in the placing and removal of the skins.

I would state in conclusion that while the illustrated example constitutes a practical 30 embodiment of my invention, I do not limit myself strictly to the exact details herein illustrated, since, manifestly, the same can be considerably varied without departure from the spirit of the invention as defined in 35 the appended claims.

Having thus described my invention, I claim:

1. A stretcher device including stretcher elements having means thereon at their lower portions in a plane to secure the same beneath a table top and including members extending laterally outward from their connection with said securing means, then rising from said outwardly extending portions 45 and then directed laterally inward from the rising portions in a plane sufficiently above the securing means to lie above the table top.

2. A stretcher of the class described adapted to be disposed adjacent to an edge of a 50 table and comprising fixed and relatively movable stretcher elements having members to overlie the table as well as downwardly extending members at the outer ends of the first mentioned members, and members 55 extending laterally inward from said downwardly extending members in a plane to lie beneath the table top, and means to secure the said inwardly extending members beneath the table top; together with actuating 60 means for the relatively movable members positioned to lie with the securing means beneath the table top.

3. A stretcher of the class described adapted to be disposed adjacent to a side edge of a table and comprising fixed and relatively 65 movable stretcher elements having members to overlie the table as well as members adapted to extend beneath the table top, means to secure the second members beneath the table top, and actuating means for the movable element, said actuating means including an element operatively connected with said movable element and projecting laterally outward to extend beyond the table and be subject to lateral pressure by the operator. 75

4. A stretcher of the class described adapted to be disposed adjacent to a side edge of a table and comprising fixed and relatively movable elements, each element having members adapted to overlie the table 80 as well as members adapted to extend beneath the table, means to secure the second-mentioned members beneath the table top, and operating means connected with the said movable element beneath the table top, 85 and having a member projecting laterally outward to be disposed beyond the table and adapted to receive the pressure of the operator.

5. In a stretcher of the class described, 90 stretcher elements approximately U-shaped, one arm of each U-shaped element having means adapted to overlie a table top, and the other arm adapted to be disposed beneath the table top, and means to move one of said U-shaped elements relatively to the other. 95

6. A stretcher of the class described comprising a base plate adapted to be secured to a table top at the under side, a U-shaped 100 stretcher element fixed to said base and having stretcher arms extending laterally inward above the base to lie above the table top, a second U-shaped stretcher element having a stretcher arm disposed adjacent to the first stretcher arm and having a member slidably secured to said base, and means to actuate said slidable stretcher element. 105

7. A stretcher of the class described comprising a base plate adapted to be secured to a table top at the under side, a U-shaped 110 stretcher element fixed to said base and having stretcher arms extending laterally inward above the base to lie above the table top, a second U-shaped stretcher element having a stretcher arm disposed adjacent to the first stretcher arm and having a member slidably secured to said base, and a lever connected with said movable element to actuate the same, said lever having its outer end in the form of a pivoted pressure arm 115 adapted to receive pressure by the operator of the stretcher. 120
